United States Patent Office.

ELI J. MANVILLE OF WATERBURY, CONNECTICUT, ASSIGNOR TO HIMSELF AND E. M. JUDD, OF WOLCOTTVILLE, CONNECTICUT,

Letters Patent No. 74,394, dated February 11, 1868.

IMPROVED MACHINE FOR MAKING SEWING-MACHINE NEEDLES.

The Schedule referred to in these Letters Patent and making part of the same.

TO ALL WHOM IT MAY CONCERN:

Be it known that I, ELI J. MANVILLE, of Waterbury, in the county of New Haven, and State of Connecticut, have invented, made, and applied to use a certain new and useful Improvement in Machines for Making Sewing-Machine Needles; and I do hereby declare the following to be a full, clear, and exact description of the said invention, reference being had to the annexed drawing, making part of this specification, wherein—

Figure 1 is a plan of the machine.

Figure 2 is a vertical section at the line $z z$.

Figure 3 is an elevation of the cutter that reduces the wire to form the needle.

Figure 4 is an elevation of the clamping-die that holds the needle-blank.

Figure 5 is an elevation of the grooving-mechanism, the bed being in section.

Similar marks of reference denote the same parts.

This invention relates to a machine in which the piece of steel wire forming the needle-blank is grasped by one of the jaws, in a series of jaws, moved around progressively, the successive movements presenting the blank, first, to a cutter that turns off the metal to form the needle, the blank being revolved as the cutter is moved up to it; second, to a grooving-tool that cuts the thread-groove; third, to a second grooving-tool that cuts the groove on the other side of the needle; fourth, to a punch that forms the needle's eye; fifth, to a polishing-wheel, or to a pointing-wheel, or both, after which the needle is removed from the jaws.

By this machine, the needle is made with great rapidity and accuracy, and without requiring handling.

In the drawing, α is a suitable frame or bed, upon which a hollow column, b , is attached, and supports at its upper end the circular bed c , that carries the respective slides and tools hereafter enumerated, and also is provided with the cam-ring d , within which is the revolving bed e , that carries the stocks f of the spindles g . This revolving bed e is upon a hollow axis, h , at the bottom of which is a ratchet-wheel, k , having the same number of teeth that there are stocks, f . I make use of any suitable pawl to operate on the ratchet-wheel k , and move the bed e , and parts it carries, periodically.

I have shown a slide, l , carrying a pawl, l' , that is acted upon by a pin in the disk m , on the shaft m' . m' is a shaft and pinion 2, to rotate the wheel 3 and shaft m' .

The spindles g are each provided with a head, n , at one end, and a pinion, o , at the other end, fitted to slide endwise on a feather or in a groove; and the pinion has a neck, q , in which is the fork 5 of the slide o' . 6 is a pin on the slide o' , entering a cam-groove, 7 , in the edge of the ring d . This groove 7 is so shaped that it allows a spring, 8 , to move the pinion o into contact with a revolving bevel-wheel, p , on a shaft, p' , that is rotated by competent power, but when the operation performed upon the needle carried by the spindle g is such that it requires to remain stationary, the cam-groove 7 draws the pinion along endwise out of contact with the wheel p . Each of the spindles g is provided with a blank-holding clamp, i , composed of two swinging nippers introduced in a slot in the head n .

The needle-blanks are supplied automatically, or by hand, into a groove in the upper end of a slide, g , the end of the blank projecting. This slide g is moved backwards and forwards by a cam, q' , driven by the shaft q'' , and gears, $r r'$, and forces the jaws i together, so as to gripe the blank firmly that is placed between them. The slide g is then drawn back by a spring, or other competent means, allowing the blank and holder to be moved to the next position. s is a stock, having a hole through it that is of the same size as the wire-blank, and on the outer side is a stationary cutting-tool, that is so adjusted as to turn off the proper amount of metal, and leave the needle of the desired size. The tool and stock are moved up over the wire-blank as it is revolved. In order to move this stock s , and the other sliding stocks hereafter named, any suitable means may be employed.

I have shown a cam-ring, t , with teeth around its edge, gearing into the wheel g , on the shaft q' , said cam-ring moving within a flange surrounding the bed e , and having a corresponding number of cams to the number of stocks, f . A pin or projection, t' , (see fig. 5,) on the under side of each of the sliding stocks, e , in contact with the cam on t , causes the movement of said stocks s , at the proper time.

The grooving of the needle is effected by the revolving cutters, u u' , mounted on the respective sliding stocks s , actuated as aforesaid, only the pin under the stock of the cutter u' is in such a position that it will not be moved as far as the cutter u . These cutters are driven by suitable power, and operate upon the needle, while it is supported in a groove in the stock below the cutter.

In order to hold the mandrels g and heads n in the proper position when stationary, I employ the rim 11 , upon the edge of which the head n rests. This rim is removed at the points where the mandrel and head revolve. I cause the needle to be turned over in passing from the grooving-tool u to the tool u' , by the action of a spring, 12 , (see fig. 6,) that throws up one side of the head, n , as it passes over its end, turning down the other side of the head into the opening in the rim, 11 , and the head coming in contact with the edge of the rim, 11 , as the movement of the mandrel and head is completed, causes said head to be fully turned over, so that the other side of the needle shall be presented to the grooving-tool, u' . The needle is next carried to the punch 13 , that is forced down at the proper time, and punches the eye of the needle. From this the needle passes to the polishing-wheel, v , for smoothing off the exterior surface of the needle, as said needle is revolved in contact with the same by the means before described.

The pointing may be done by hand, or one or more wheels may be placed so as to grind the point of the needle as it is presented, and revolved as aforesaid.

The needle is finally delivered from the machine by being relieved from the jaws i , a sliding opener being employed to act on the outer ends of the jaws, to turn them into the position shown in fig. 1, at 14 .

What I claim, and desire to secure by Letters Patent, is—

1. The sliding stock s , having a hole corresponding to the size of the needle-blank, with an adjustable cutter outside said stock, in combination with the revolving spindles g , arranged as shown, and moved progressively, so as to present the needle-blanks successively to the operation of said cutter, while the blank is being revolved as set forth.
2. The spindle g , rim 11 , wheel p , and sliding bevel-gears o , in combination with the springs 8 and grooved cam 7 , (or equivalent mechanism for moving the gears o), all arranged in such a manner that the needle-blank will be revolved while being turned, and will be held in a fixed position while being grooved and punched, substantially as set forth.
3. The holding-jaws i and heads n , upon the spindles g , in combination with the sliding blank-supplier g , substantially as and for the purposes set forth.
4. The general arrangement and combination of the blank-supplying slide q , the spindles g , the jaws i , the turning-mechanism, the grooving and punching-devices, and the means for revolving and for holding the spindles during the respective operations, substantially as set forth.

In witness whereof, I have hereunto set my signature, this 7th day of October, A. D. 1867.

E. J. MANVILLE.
